UNITED STATES PATENT OFFICE.

BERT R. WILLIAMSON, OF FAIRFIELD, MAINE, ASSIGNOR TO KEYES FIBRE COMPANY,
OF WATERVILLE, MAINE, A CORPORATION OF MAINE.

BUNDLING-MACHINE.

1,401,298.

Specification of Letters Patent. Patented Dec. 27, 1921.

Application filed October 8, 1919. Serial No. 329,572.

To all whom it may concern:

Be it known that I, BERT R. WILLIAMSON, a citizen of the United States, residing at Fairfield, county of Somerset, State of Maine, have invented an Improvement in Bundling-Machines, of which the following description, in connection with the accompanying drawing, is a specification, like characters on the drawing representing like parts.

This invention relates to a machine for bundling articles and is especially designed for use in putting up bundles of pulp or paper pie plates, butter dishes, and similar articles. Such articles are usually stacked in piles or rolls of the desired number, as five hundred, wrapped in heavy paper, and tied with twine running longitudinally and transversely around the pile or roll.

20 A machine for this purpose is disclosed in the patent to M. L. Keyes No. 921,256 granted May 11, 1909, and the present invention is an improvement thereon.

The object of the present invention is to 25 simplify the construction and operation of a machine of this type.

The object of the invention is further to provide in such a machine quick acting means for operating the movable head to 30 compress the articles.

These and other objects and features of the invention will appear more fully from the accompanying description and drawings and will be particularly pointed out in the 35 claims.

The drawings show the complete bundling machine embodying a preferred form of the invention.

In the drawings—

40 Figure 1 is a view in side elevation of the machine.

Fig. 2 is a view in side elevation and partially in vertical cross section of the right hand head support, head, and means for 45 operating the head.

Fig. 3 is a view in end elevation showing the upper portion of the right hand end of the machine.

The supporting standard of the machine 50 comprises a bed 1 extending longitudinally at a suitable height from the floor and of any desired length determined in general by the length of the bundles to be formed in the machine. This bed is conveniently supported near the left hand end by a pair of

legs 2 mounted on casters 3, and near the right hand end by a single leg 4. This provides an easy means by which the machine may readily be moved about the room where it is used. This may be done by lifting the 60 end of the machine having the single leg 4, and then rolling it along on the casters 3.

A pair of oppositely disposed heads are mounted from the bed, and one, preferably both, of these heads are longitudinally adjustable upon the bed. Preferably also the heads are carried in head supports and the longitudinal adjustment is secured by adjusting the head supports upon the bed.

The right hand head support 5 has a depending rib 6 fitting in a longitudinal groove in the bed whereby the head support is guided in its longitudinal adjustment.

The head support is clamped in position by a bolt 7 extending through a transverse recess in the bottom of the head support and provided with oppositely disposed clamped blocks 8 beveled as indicated in Fig. 3 above and below the clamping bolt to engage corresponding bevels on the base of the head support and the top of the bed. The left hand head support 9 is similarly constructed and capable of similar adjustment by means of a similar clamping bolt 10. It will thus be seen that by loosening the clamping bolt 85 either head support may be moved along the bed to the desired position and by tightening the clamping bolt may be locked in its adjusted position. Either or both of the clamping bolts may be provided with a 90 handle 11 by means of which it may be readily turned to clamp and unclamp.

The heads which are carried by the respective head supports are preferably of the skeleton like form shown in the patent to 95 Keyes above referred to and conform in general to the exterior surfaces of the articles, such as pie plates, to be bundled. The left hand head 12 is shown as adapted to fit the concave surface of the article at the left 100 hand end of the bundle, and is carried upon a spindle mounted in the barrel of the head support 9.

The right hand head 13 is of similar form but is adapted to fit the convex surface of 105 the article at the right hand end of the bundle. This head is also provided with a spindle 14 which fits into a sleeve 15 adapted to slide longitudinally in the barrel 16 of the right hand head support 5.

It will thus be seen that the heads with their connected spindles may readily be removed thus allowing heads of any desired shape and size to be fitted into the machine.

5 Both heads may be provided with intersecting grooves to receive the bundling cord as described and illustrated in the patent to Keyes, above referred to.

After the head supports have been adjusted upon the bed to their proper relative positions to receive the stack or pile of articles to be bundled, one or the other or both of the heads are moved longitudinally to compress the stack or pile of articles. In 10 the construction illustrated this result is secured by moving the right hand head. In the patent to Keyes above referred to this movement was secured by a screw which secured the desired compression but which 15 was comparatively slow in its action. An important feature of this invention is to provide a means by which the compressing movement of the head is secured quickly and by a single movement of the hand of the 20 operator, and a simple and preferred construction for effecting this result is illustrated.

A lever is provided comprising a yoke shaped section 17, the legs 18 of which 30 straddle the barrel 16 of the head support, and a handle section 19 which is made of sufficient length to secure the requisite leverage when operated by hand. This lever is fulcrumed to the barrel 16 of the head support by a pin 20 passing transversely therethrough and held in place by a cotter pin 21. A plurality of holes 22 are provided in the 35 legs 18 for engagement with the fulcrum pin 20. The lever is provided with a link connection to the head. This connection is effected by a pair of rods 23 mounted one at 40 each side of the barrel 16 of the head support and pivoted at one end at 24 to the left hand end of the sleeve 15, and pivoted at the other end at 25 to the legs 18 of the lever. These rods 23 are preferably made in two 45 sections threaded together at 26 thus enabling the length of the link to be adjusted.

When the head is in its retracted position 50 the lever handle 19 preferably stands vertically as shown in Figs. 1 and 2. When in this position the pile or stack of articles to be bundled is placed between the heads and then the operator grasps the handle 19 and 55 swings the lever about its fulcrum 20 to the left thus projecting the head longitudinally and compressing longitudinally the pile or stack of articles to be bundled. This movement is accomplished by a single swing of 60 the hand. As the handle comes down to horizontal position the pivotal connection 25 passes the line running through the lever fulcrum 20 and the pivot 24 connecting the link and head, and some portion of the lever 65 and link structure such as the yoke 17 comes

into contact with some fixed portion of the machine such as the upper surface of the barrel 16 of the head support, and thus the head is locked in its projected position. When the bundle has been wrapped and tied 70 this lock is broken by raising the handle slightly and returning it or allowing it to return to its upright position. The extent of longitudinal projecting movement given to the head may be adjusted by setting the 75 fulcrum pin 20 into one or the other of the holes 22 and also by adjusting the length of the links 23.

There is thus provided a simple, strong, and quick acting construction for projecting 80 the head to compress the articles to be bundled, and one in which at the end of the compressing stroke of the lever the parts are automatically locked to enable the bundling to be performed.

The stack or pile of plates or other articles is supported in proper alinement with the heads by a mechanism similar in its general features to that illustrated in the patent to Keyes above referred to, but one in which 90 the construction has been simplified. The articles are supported upon a pair of longitudinally extending supporting bars 26. These are arranged to support the articles at two widely separated points so that the 95 articles are held in proper alinement with the axis of the heads. They are made simultaneously adjustable in such a manner that they always remain parallel with the axis of the heads, but move toward and from 100 the axis on substantially radial lines so that whatever the diameter or size of the articles may be they are supported at two similar or symmetrically disposed points. These supporting bars 26 are preferably hollow tubes 105 or cylinders and are bolted to plates at their ends by the bolts 27 extending centrally therethrough.

At the right hand end of the machine the bed 1 is provided with a rigid downwardly projecting bracket 28 and at the left hand end with a rigid laterally projecting bracket 29. A shaft 30 extends longitudinally of the bed and is journaled in the brackets 28 and 29. At its left hand end it carries a plate 31 and at its right hand end a plate 32 between which one of the bars 26 is bolted. The shaft 30 also carries rigid therewith adjacent the plates 31 and 32 respectively the gears 33 and 34. The other bar 26 115 is supported at its right hand end in a plate 35 mounted upon a trunnion 36 in the plate 28 and having rigidly connected thereto a gear 37 meshing with the gear 34, while at its left hand end this bar is mounted in a plate 38 upon a similar trunnion having a similar gear meshing with the gear 33. The plate 32 is extended downwardly below the shaft 30 and provided with a segmental slot 39 fitting over a screw bolt 40 in the plate 120 130.

28. This screw bolt is preferably provided with an operating handle 41. It will thus be seen that upon loosening the screw bolt 40 either bar 26 may be swung toward or 5 from the axis of the heads and that thereupon because of the gear connection the other bar 26 will move in a similar manner and to a similar extent. Thus the bars may be brought, along substantially radial lines, 10 into position to support articles, of any diameter in axial alinement with the heads. When the bars have been brought into proper position they are locked in place by screwing up the bolt 40.

15 The operation of the machine otherwise is substantially as described in the patent to Keyes above referred to and as the placing in position of the wrapping paper and cords is fully described therein it is not here re- 20 peated.

Having thus described my invention what I claim as new and desire to secure by Letters Patent is—

1. A bundling machine comprising a 25 standard, a pair of oppositely disposed heads mounted thereon, means for supporting a stack of articles to be bundled between said heads, a head support on said standard, one of said heads mounted for longitudinal 30 movement in the head support, a lever fulcrumed upon and transversely of the head support, a link pivoted to the longitudinally movable head and to the lever whereby the head will be projected longitudinally on the 35 head support when the lever is swung about its fulcrum, and means for locking the head in its projected position.

2. A bundling machine comprising a standard, a pair of oppositely disposed heads 40 mounted thereon, means for supporting a stack of articles to be bundled between said heads, a head support on said standard, one of said heads mounted for longitudinal movement in the head support, a lever fulcrumed upon and transversely of the head support, a link pivoted to the longitudinally movable head and to the lever whereby the head will be projected longitudinally on the head support when the lever is swung about 45 its fulcrum, a portion of the lever and link engaging with a fixed portion of the machine when the lever is swung sufficiently to bring the pivot connecting the lever and link past the line running through the lever ful- 50 crum and through the pivot connecting the

link and head whereby the head is locked in projected position.

3. A bundling machine comprising a standard, a pair of oppositely disposed heads mounted thereon, means for supporting a 60 stack of articles to be bundled between said heads, a head support on said standard, one of said heads mounted for longitudinal movement in the head support, a lever having a yoke shaped section fulcrumed upon 65 and straddling the head support, links pivoted to the yoke shaped section and to the head whereby the head will be projected longitudinally on the support when the lever is swung about its fulcrum and whereby when 70 the lever is swung sufficiently to bring the yoke shaped section into engagement with the head support the pivot connecting the lever and links will have passed the line running from the lever fulcrum to the pivot 75 connecting the links and head, thus locking the head in projected position.

4. A bundling machine comprising a standard, a pair of oppositely disposed heads mounted thereon, means for supporting a 80 stack of articles to be bundled between said heads, a head support on said standard, one of said heads mounted for longitudinal movement in the head support, a lever fulcrumed upon and transversely of the head 85 support, a link pivoted to the longitudinally movable head and to the lever whereby the head will be projected longitudinally on the head support when the lever is swung about its fulcrum. 90

5. A bundling machine comprising the construction defined in claim 4 together with means for adjusting the extent of longitudinal movement imparted to the head by rocking the lever. 95

6. A bundling machine comprising the construction defined in claim 4 together with means for adjusting the distance between the point where the link is pivoted to the lever and the fulcrum of the lever thereby to adjust the longitudinal movement given to the head by rocking the lever. 100

7. A bundling machine comprising the construction defined in claim 3 together with means for adjusting the yoke shaped section 105 with respect to the fulcrum to vary the extent of longitudinal movement of the head.

In testimony whereof, I have signed my name to this specification.

BERT R. WILLIAMSON.
